LOUIS MUTTI, OF PARIS, FRANCE

POWDER-SUPPLYING DEVICE WITH ADJUSTABLE FEED

Application filed February 27, 1929, Serial No. 343,188, and in France March 5, 1928.

The present invention relates to a powder-supplying device whose output can be suitably regulated.

The device or powder holder chiefly comprises the combination of a case of suitable form whether round, oval, polygonal or the like in which is a peripheral powder chamber adapted to contain the supply of powder and provided with a piston whose shape corresponds to that of the said chamber and which cooperates with a driving spring. The chamber is in open communication at the bottom part with an operating device provided with controlling means by which the operating device can be given a movement of oscillation or rotation, or a straight movement in either direction, continuous or alternating, for moving the powder from the chamber to a central conduit, the operating device comprising suitable driving parts in eccentric position, extending from the periphery to the centre and leading to the central conduit, a closure being provided at the top of the conduit which is optionally removable, and is apertured for the delivery of the powder, the whole apparatus being provided with a loose or hinged cover, between which cover and the said closing device of the conduit is a chamber adapted to contain a powder puff or the like, which is to be supplied with powder by the operation of the feeding device or distributer.

In the accompanying drawings which show by way of examples various embodiments of the invention:

Fig. 1 is a vertical section of a first embodiment and,

Fig. 2 is the corresponding plan view with the cover removed.

Fig. 3 is a detail view of the distributer.

Fig. 4 is a horizontal section on the line IV—IV of Fig. 1, showing another form of distributer.

Figs. 5 and 6 are fragmentary vertical sections of modifications of the devices controlling the distributer adapted for continuous motion.

Figs. 7 and 8 are elevations partly in section of modifications of the box with movable bottom.

Fig. 9 is a partial plan view of Fig. 7.

Fig. 10 is a vertical section of a modification of Fig. 8.

In the forms of construction shown in Figs. 1 and 2, the receptacle comprises a box 1 provided with a hinged cover 2 and having an annular flange 3 formed in one with an annular partition 4, leaving in the interior of the said box a space or chamber 5 adapted to contain the powdered material to be supplied.

At the central part of the chamber 5, is a conduit 6 formed in one with a disk 7 which may be fitted to the flange 3 by a bayonet joint.

The under side of the disk 7 is in contact with a spring 10, downwardly urging a piston 11 which herein consists of an annular disk of suitable material. Upon the disk 7 is mounted a concave member 12 comprising the perforations 13 of any desired shape and disposition adapted to supply the powder to a flat powder puff (not shown) which is disposed between the said concave member and the cover 2.

The said conduit 6 and the partition 4 do not extend to the bottom of the box 1, and in the said bottom part is mounted a feeding device or distributer 14 which in the example shown in Figures 1 to 3 consists of a disk having below the chamber 5 a cut-out part 15 bounded by sets of curved surfaces 16 and 17 in eccentric position, the surfaces of a given group having a symmetrical disposition.

The said distributer 14 comprises an operating knob 18 traversing a slot in the box 1.

To fill the box, the person removes the cover 2. Then by taking out the device formed by the disk 7 and the concave member 12, he also removes the spring 10 and the piston 11 which may if desired be attached to the disk 7. The proper amount of powder is placed in the box, after which are inserted the piston 11 with its spring and also the disk 7 and the concave member 12, which are secured by a bayonet joint.

To supply the powder which has thus been placed in the box, the person gives to the knob 18 a circular reciprocating motion during the displacement of the feeding device in

the direction of the arrow, Figure 3; and the surfaces 16 will thus drive the powder from the periphery to the centre, the powder descending by the action of the spring 10 and the piston 11.

During the displacement of the distributor 14 in the contrary direction to the arrow 3, the surfaces 16 are inactive but the surfaces 17 now act to drive the powder from the 10 periphery towards the centre.

The powder being thus driven to the centre, it will rise through the conduit 6 and will escape through the feeding perforations 13 in order to impregnate the powder puff 15 (not shown) which is disposed in the concave member 12. The chambers 5 and 6 herein act as communicating vessels, and the powder tends to proceed through the conduit 6 by the action of the spring to which is 20 added that of the distributor 14.

The distributor 14, shown in Fig. 3 which supplies the powder for both directions of rotation, may be replaced by the arrangement shown in Fig. 4, and herein a ring 19 25 having in the interior the eccentric arms 20 of suitable curvature, comprises on the periphery a set of ratchet teeth cooperating with the elastic pawl 21 carrying the operating knob 18. A stop 22 allows the displacement 30 of the ring 19 only in one direction.

It is feasible to provide upon the periphery of the ring 19 a set of gear teeth as shown in Fig. 5, cooperating with a wheel 24 provided with an operating knob 25, or as shown in 35 Fig. 6, to provide upon the said ring a rack 26 cooperating with a pinion 27 secured to an operating knob 28.

The distributor may also be operated by the use of a movable box bottom 29, as shown 40 in Figs. 7 to 9, and herein the distributor is mounted on this bottom, which latter is held in place by a flange 30 (Fig. 7) or an annular groove 31 (Fig. 8).

In these several forms of construction, the 45 box 1, has a circular form in the interior, but the external form might be varied according to needs, and the said box may receive all desired ornaments or decorations.

The interior of the box may have other 50 shapes such as square, triangular, polygonal or the like, and the distributor 14 may be given a straight motion, it having a suitable shape, with a central aperture 15, so that the powder will rise by this motion. The arms 55 or surfaces of the distributor may have all desired curves and inclinations, and said arms may even have a straight form, with all necessary inclination.

The arrangement herein described may be 60 inverted, and herein the powder chamber consists of the central conduit 6 of the proper size, and the supply takes place through the annular part 5, while suitably modifying the direction of movement of the distributor (for 65 instance the one shown in Fig. 4) as indicated

in Figure 8. It is feasible in certain cases to dispense with the distributor 14, and the spring 10 may be replaced by a suitable pressure device.

The invention is adapted for the supply 70 of all varieties of powder, and chiefly for face powder.

What I claim is:

1. A powder supplying device comprising a casing, a powder storage chamber in the 75 casing, a perforated disc supported above the chamber, a cover on the casing and spaced from the disc to provide a space to receive a powder puff, a spring pressed plunger in the casing for maintaining the powder under pressure, a discharge conduit in communication with the powder chamber and the perforations in the disc, a rotatable means in the casing adapted to force the powder from the storage chamber and through the discharge 80 conduit and the perforations and means for rotating the last-mentioned means.

2. A powder supplying device comprising a casing, a powder storage chamber in the 90 casing, a perforated disc supported above the chamber, a cover on the casing and spaced from the disc to provide a space to receive a powder puff, a spring-pressed plunger in the casing for maintaining the powder under pressure, a discharge conduit in communication with the powder chamber and the perforations in the disc, a rotatable means in the 95 casing adapted to force the powder from the storage chamber and through the discharge conduit and the perforations, means for rotating the last-mentioned means, the rotating 100 means consisting of a bottom portion mounted for rotation on the casing.

3. A powder supplying device comprising a casing, a powder storage chamber in the 105 casing, a perforated disc supported above the chamber, a cover on the casing and spaced from the disc to provide a space to receive a powder puff, a spring pressed plunger in the 110 casing for maintaining the powder under pressure, a discharge conduit in communication with the powder chamber and the perforations in the disc, a rotatable means in the casing adapted to force the powder from the storage chamber and through the discharge 115 conduit and the perforations, and means for rotating the last-mentioned means, the rotatable means consisting of arms movable through the storage chamber and the discharge conduit.

4. A powder supplying device comprising a casing, a powder storage chamber in the 120 casing, a perforated disc supported above the chamber, a cover on the casing and spaced from the disc to provide a space to receive a powder puff, a spring pressed plunger in the 125 casing for maintaining the powder under pressure, a discharge conduit in communication with the powder chamber and the perforations in the disc, a rotatable means in the 130

casing adapted to force the powder from the storage chamber and through the discharge conduit and the perforations and means for rotating the last-mentioned means, the rotatable means consisting of curved arms movable through and at the bottom of the storage chamber and the discharge conduit.

5. A powder supplying device comprising a casing, a powder storage chamber in the casing, a perforated disc supported above the chamber, a cover on the casing and spaced from the disc to provide a space to receive a powder puff, a spring pressed plunger in the casing for maintaining the powder under pressure in the storage chamber, a discharge conduit in communication with the powder chamber and the perforations in the disc, a rotatable means in the casing adapted to force the powder from the storage chamber and through the discharge conduit and the perforations, and means for rotating the last-mentioned means.

10. A powder supplying device comprising a casing, a powder storage chamber in the casing, a perforated disc supported above the chamber, a cover on the casing and spaced from the disc to provide a space to receive a powder puff, a spring pressed plunger in the casing for maintaining the powder under pressure in the storage chamber, a discharge conduit in communication with the powder chamber and the perforations in the disc, a rotatable means in the casing adapted to force the powder from the storage chamber and through the discharge conduit and the perforations, and means for rotating the last-mentioned means.

15. A powder supplying device comprising a casing, a powder storage chamber in the casing, a perforated disc supported above the chamber, a cover on the casing and spaced from the disc to provide a space to receive a powder puff, a spring pressed plunger in the casing for maintaining the powder under pressure in the storage chamber, a discharge conduit in communication with the powder chamber and the perforations in the disc, a rotatable means in the casing adapted to force the powder from the storage chamber and through the discharge conduit and the perforations, and means for rotating the last-mentioned means.

20. A powder supplying device comprising a casing, a powder storage chamber in the casing, a perforated disc supported above the chamber, a cover on the casing and spaced from the disc to provide a space to receive a powder puff, a spring pressed plunger in the casing for maintaining the powder under pressure in the storage chamber, a discharge conduit in communication with the powder chamber and the perforations in the disc, a rotatable means in the casing adapted to force the powder from the storage chamber and through the discharge conduit and the perforations, and means for rotating the last-mentioned means.

25. A powder supplying device comprising a casing, a powder storage chamber in the casing, a perforated disc supported above the chamber, a cover on the casing and spaced from the disc to provide a space to receive a powder puff, a spring pressed plunger in the casing for maintaining the powder under pressure in the storage chamber, a discharge conduit in communication with the powder chamber and the perforations in the disc, a rotatable means in the casing adapted to force the powder from the storage chamber and through the discharge conduit and the perforations, and means for rotating the last-mentioned means.

In testimony whereof I have hereunto set my hand at Paris, this 13th day of February,

25 1929.

LOUIS MUTTI.
